(57) **CLAIM**

The ornamental design for a infusion site retainer, as shown and described.

DESCRIPTION

FIG. 1 is a perspective view of an infusion site retainer according to one embodiment.

FIG. 2 is a top side view of the infusion site retainer of FIG. 1.

FIG. 3 is a bottom side view of the infusion site retainer of FIG. 1.

FIG. 4 is a right side view of the infusion site retainer of FIG. 1.

FIG. 5 is a left side view of the infusion site retainer of FIG. 1.

FIG. 6 is a front side view of the infusion site retainer of FIG. 1.

FIG. 7 is a back side view of the infusion site retainer of FIG. 1.

FIG. 8 is a perspective view of another embodiment of an infusion site retainer including one tubing guide and one tubing stop disposed on an upper top surface of the infusion site retainer.

FIG. 9 is a top side view of the infusion site retainer of FIG. 8.

FIG. 10 is a bottom side view of the infusion site retainer of FIG. 8.

FIG. 11 is a right side view of the infusion site retainer of FIG. 8.

FIG. 12 is a left side view of the infusion site retainer of FIG. 8.

FIG. 13 is a front side view of the infusion site retainer of FIG. 8; and,

FIG. 14 is a back side view of the infusion site retainer of FIG. 8.

In FIGS. 1-7, the broken lines illustrating grommets configured to receive straps for attachment of the infusion site retainer to a patient are for illustrative purposes only and form no part of the claimed design.

In FIGS. 1-7, the broken lines illustrating tubing guides and tubing stops are for illustrative purposes only and form no part of the claimed design.

In FIGS. 8-14, the broken lines illustrating grommets configured to receive straps for attachment of the infusion site retainer to a patient are for illustrative purposes only and form no part of the claimed design.

In FIGS. 8-14, the broken lines illustrating two tubing guides and five tubing stops are for illustrative purposes only and form no part of the claimed design.
